TILE PANEL

Richard H. Monroe, R.F.D., Bolivar, N.Y.

Filed Nov. 25, 1963, Ser. No. 77,552

Term of patent 14 years

(Cl. D18—2)

FIG. 1 is a plan view of a tile panel illustrating the design of the present invention; and

FIG. 2 is a transverse sectional view of the tile panel taken on line 2—2, FIG. 1.

The side edges and rear face of the tile panel of the present invention are planar.

I claim:

The ornamental design for a tile panel, substantially as shown and described.
